LUGGAGE HANDLE
Filed May 22, 1936

Fig. 1

A technical drawing showing a mechanical assembly. It features a base with several rectangular cutouts. Two circular holes are visible on the left side. A central vertical structure is labeled '15'. To the left of the base, two labels are present: '10' pointing to a vertical slot and '11' pointing to a horizontal slot. To the right, a label '29' is at the top, and '25' is on the right side of the central structure. The drawing is done with heavy black lines and some cross-hatching.

LUGGAGE HANDLE

Emile Garfinkel, Newark, N. J.

Application May 22, 1936, Serial No. 81,263

2 Claims. (Cl. 190—57)

This invention relates, generally, to improvements in carrying handles for portable luggage, cases and similar articles; and the invention has reference, more particularly to a collapsible flat-lying handle capable of being expanded to upwardly bowed condition for insertion of the hand thereunder whereby the same may be comfortably grasped when employed in carrying the luggage, case or the like to which it is applied; means being provided for releasably latching the handle in such upwardly bowed condition.

This invention has for an object to provide a longitudinally flexible handle having internal spring means normally tending to depress the same to a flat-lying position along the top of the luggage or case to which it is applied, such handle being capable of being upwardly bowed or arched, against the tension of its spring means, to an expanded position subject to the grasp of the carrier's hand; a novel latch means being provided for releasably holding the handle in the latter position until collapse thereof is desired.

Other objects of this invention, not at this time more particularly enumerated, will be understood from the following detailed description of the same.

An illustrative embodiment of this invention is shown in the accompanying drawing, in which:

Fig. 1 is a plan view of the top end of a case equipped with the novel handle structure according to this invention, the latter being shown in its collapsed flat-lying position along the case top; Fig. 2 is a longitudinal sectional view, taken on line 2—2 in Fig. 1, but drawn on a larger scale; Fig. 3 is a similar longitudinal sectional view, showing the handle expanded subject to the grasp of the user's hand, and latched in such position subject to release when it is desired to collapse the same in initial flat-lying position; Fig. 4 is an enlarged fragmentary plan view of an anchor box and the handle coupling link cooperative therewith, with portions of the handle in section; Fig. 5 is a horizontal sectional view, taken on line 5—5 in Fig. 2; and Fig. 6 is a transverse vertical section, taken on line 6—6 in Fig. 3.

Similar characters of reference are employed in the above described views, to indicate corresponding parts.

Referring to the drawing, the reference character 10 indicates a longitudinal flat spring steel core strip which extends axially through the handle body between its ends. Secured to the respective ends of said spring strip 10 are handle coupling links, comprising an inner end lug 11

upon which an end of said spring strip 10 is overlapped and secured by rivets 12, or any other suitable fastening means. Extending outwardly from the base bar 13 from which said end lug 11 springs are laterally spaced link side arms 14, the free ends of which are joined by a transverse stop bar 15, thus forming a rectangular centrally open link body. Underlying the intermediate portion of said spring strip 10 between the coupling link end lugs is a filler strip 16 of any suitable preferably non-resilient material, such as leather, paper or fibrous material. Suitably arranged to envelop the spring strip 10 are the upper and lower portions 17 and 18 respectively of the handle body, the same having loop ends 19 respectively extending the openings of the link bodies and around the link base bars 13. Said upper and lower portions 17 and 18 are joined along their longitudinal edge margins by stitching 20. Said handle body may be made of leather or any other suitable material or combination of materials, and the same may be shaped to provide such peripheral outline as is found desirable from the standpoints of both use and appearance. Each link side arm 14 is provided at its upper side and adjacent to the connecting transverse stop bar 15 with stepped latch nosings 21, the free ends of which form latching shoulders 22 rising from the upper surfaces of said link side arms 14.

Means are provided for anchoring the handle structure in operative relation to the luggage or case which it is to serve. Such anchoring means comprise hollow anchor boxes comprising top walls 23, side walls 24, outer end walls 25 and inner end walls 26. The inner end walls 26 are cut away adjacent to each side wall 24 to provide openings 27 through which the link side arms 14 may slidably extend. Projecting downwardly from the central portion of each end wall 25 and 26 are clenching lugs 28 which are pierced downwardly through the body wall 29 of the luggage or case to which the handle is to be attached. Before attaching the anchor boxes to the luggage or case wall 29, the inner end walls 26 and the clenching lugs springing therefrom are passed downwardly through the openings of the handle coupling links so as to engage the side arms 14 of the latter in and through the openings 27 of the anchor boxes, thereby assembling the latter in operative relation to said handle coupling links, whereupon the anchor boxes are attached to the luggage or case wall 29 in properly spaced apart relation, by passing the clenching lugs 28 through said wall and clenching the free ends thereof over upon the under side of the latter.

When free from any obstructing or counter-acting restraint, the handle spring strip 10 will assume a normal substantially flat longitudinally extending position which causes the handle to extend substantially in flat-lying longitudinal dis-
5 position along the wall 29 between the fixed anchor boxes, with the coupling links slid into inwardly projecting relation to and within the interior of the anchor boxes (see Figs. 1, 2, 4 and 5). When it is desired to employ the handle for carrying the luggage or case to which it is applied, said handle is grasped intermediate its ends and lifted upwardly. Such upward lifting of the handle causes the spring strip 10 to arch upwardly, and thus assume a condition of tension, while at the same time the coupling links are pulled outwardly relative to the anchor boxes until their stop bars 15 are arrested by abutment against the inner end walls 26 of said boxes, and
20 the latch nosings 21 are withdrawn exteriorly from the ends of said boxes. The tension of the arched spring strip 10 develops a tendency of its ends and the coupling links affixed thereto, to swing upwardly, which yieldably thrusts the link side arms 14 upwardly against the free inner margin 30 of the top walls of said anchor boxes, thus carrying the latch shoulders 22 of the latch nosings 21 into abutment against said margins 30 of said anchor box top walls. This engagement of the latch nosings with the anchor boxes obstruc-
25 tions the tendency of the spring strip 10 to flatten out, and consequently maintains the handle in expanded outwardly bowed relation to the luggage or case wall 29, as shown more particularly in Fig. 3.

When the handle is expanded for use in the manner above described, it will be obvious that the convenience of the user is efficiently served, since the luggage or case may be temporarily set down and the hand disengaged from the handle without tendency of the latter to collapse, and consequently the handle is retained in expanded condition subject to ready and quick use while the luggage or case is being carried about. Notwithstanding this, when it is desired to collapse the handle to normal initial flat-lying condition, so as to reduce its projection relative to the luggage or case body to a minimum, and thus more conveniently dispose the same for compact stowage of the luggage or case, as, for example, beneath car seats, in automobile luggage compartments, etc., this may quickly and easily be accomplished by merely pressing downwardly upon the arch handle until the latch nosings 21 are released from their abutting relation with the anchor box top wall margins 30, whereupon the restraint upon the spring strip 10 is removed and

the same will immediately flatten out, so as to thereby flatten down the handle as a whole, while at the same time releasing the coupling links so that the same slide inwardly into the anchor box interiors, as shown in Fig. 2.

From the above, it will be obvious that a very convenient and satisfactory collapsible handle for luggage and the like is provided; it will be understood however that various changes could be made in the disclosed construction and many apparently widely different embodiments of this invention could be made without departing from the scope thereof as defined in the hereinafter claims. It is therefore intended that all matter contained in the above description or shown in the accompanying drawing shall be interpreted as illustrative and not in a limiting sense.

I claim:—

1. A collapsible handle for luggage, comprising a handle means having a spring strip core extending longitudinally thereof, coupling loops affixed to the ends of said spring strip core and adapted to extend from the ends of said handle means, said coupling loops having side arms connected at their free extremities by a transverse stop bar, anchor boxes for fixed attachment to the luggage, said anchor boxes having inner end walls provided with openings through which said coupling links side arms move, and said coupling link side arms having latch nosings projecting upwardly therefrom and adapted to engage the anchor box ends when said coupling link side arms are drawn outwardly relative to said anchor boxes by upward bowing of said handle means and its spring strip core, whereby said handle means is releasably held up-bowed against the collapsing tension of its spring strip core.

2. A collapsible handle for luggage, comprising a longitudinally resilient normally flat-lying handle means capable of being upwardly bowed to a position for use, coupling links extending from the ends of said handle means, said coupling means having side arms connected at their free extremities by a transverse stop bar, hollow anchor boxes for fixed attachment to the luggage, said anchor boxes having inner end walls of reduced width extending through said coupling loops between their side arms and engageable by their stop bars, and said coupling side arms having upwardly off-set latch nosings adapted to engage exterior end portions of said anchor boxes when said coupling links are out-drawn from the latter by upward bowing of said handle means, thereby to hold said handle means up-bowed against its collapsing tension.

EMILE GARFINKEL.
